UNITED STATES PATENT OFFICE.

HENRY B. LITTLEFIELD, OF CLEVELAND HEIGHTS, OHIO.

APARTMENT WITH COMPANION BEDS.

Application filed April 16, 1923. Serial No. 632,552.

This invention relates to apartments with companion beds. More particularly it includes means whereby improved housing facilities are made possible and whereby the construction of each unit of the housing group will have exceptional advantages in the matter of economy of space, arrangement, and use, both as living and sleeping quarters.

Under the conditions brought about by the high real estate values and the resultant congestion in urban communities, various expedients have been resorted to to provide more space during the daytime within apartments, such as folding beds, beds concealed in closets and in various temporary and built-in articles of furniture. Buildings have also been made to accommodate beds in special recesses formed under the flooring of certain of the rooms and closets. In many of such arrangements, however, there is the disadvantage of placing the bed in a portion of the building where it does not receive sufficient light and air, and in certain localities there are regulations to prevent such unsanitary features of apartments with positive requirements that folding beds be placed in outside walls of a building and receive adequate light and air. Such regulations accordingly limit the variety of floor plans which may be introduced in apartment houses without going to extraordinary expense.

In my Patent No. 1,443,582, granted January 30, 1923, I have set forth one means of avoiding the disadvantages referred to.

The object of my present invention is to provide a type of building, modified but slightly from standard construction, and co-operating with companion beds to economize space and permit flexibility of plan of housing structures. Another object of the invention is to provide a special type of companion beds co-operating with the special construction of building mentioned. Other objects of the invention will appear in the course of the following description. To the accomplishment of the foregoing and related ends, said invention, then, consists of the means hereinafter fully described and particularly pointed out in the claims.

The annexed drawing and the following description set forth in detail certain structure embodying the invention, such disclosed means constituting, however, but one of

various structural forms in which the principle of the invention may be used.

In said annexed drawing:

Fig. 1 is a sectional view of a building showing two adjoining rooms with companion bed units in each of said rooms; Fig. 2 is a similar view showing one bed in raised and one in lowered position; Fig. 3 is a similar view showing the companion beds in one room, one of said beds being in stored position; Fig. 4 is an end view of the beds shown in Fig. 3; Fig. 5 is a view similar to Fig. 4 but showing the lower bed of narrower width and inwardly positioned plunger legs upon the upper bed; Fig. 6 is a perspective view partially in section showing a portion of a building and the relation of the companion beds thereto; Fig. 7 is a perspective view showing one of the companion bed units; Fig. 8 is a perspective view showing two companion bed units in stored or nested position; the springs, mattress, and other appurtenances being in place; Fig. 9 is a plan view of the bed showing one form of counter-balancing mechanism; Fig. 10 is an enlarged center sectional view of the central portion of the counter-balancing mechanism; Fig. 11 is an elevation showing a plunger leg for attachment to a bed unit; Fig. 12 is an enlarged vertical sectional view of one of the plunger legs and the trigger latch and its associated mechanism; Fig. 13 is a horizontal sectional view of the plunger leg taken through the double pulley, taken along the line 13—13 shown in Fig. 12, looking in the direction of the arrows; Fig. 14 is a horizontal sectional view of the corner post of a bed unit taken through the center line of a clasp attachment and showing the pulley box in top plan, taken along the line 14—14 shown in Fig. 11, looking in the direction of the arrows; Fig. 15 is a horizontal sectional view showing the part of the clasp attachment which is first adjusted and bolted to an upright corner post of a bed unit, taken along the line 15—15 shown in Fig. 11, looking in the direction of the arrows; Fig. 16 is an elevation of the part shown in Fig. 15; Fig. 17 is an enlarged fragmentary sectional view showing the channel groove in the plunger leg to accommodate the operating cable and its pulley; Figs. 18 to 19 are enlarged sectional fragmentary views showing the means for guiding and positioning the cable adjacent the pulley leg; and

2
Fig. 20 is an end view of one of the hangers used along the operating cables to support and guide the trigger cords.

As has been indicated, the invention is 5 adaptable for individual buildings, and also lends itself to incorporation in a building group conforming in artistic arrangement with a general plan in such building group. In such building group it is possible to ar- 10 range in each building unit the grouping of individual living apartments in the most desirable relation to each other so as to provide for the maximum of light and air for the living and sleeping rooms as well as to pro- 15 vide for the other features considered in locating a house upon a building site. Such units may be called house apartments in distinction to the well known apartment house type of structure and said units when so ar- 20 ranged in groups may be provided with the usual combined heating and lighting and other services as is customary in apartment house structures.

Whether used in a single building or in a 25 group arrangement it will be noted that one room of exceptional size is provided and that by means of an opening in the base of the dividing wall between two of the rooms ad- 30 jacent the baseboard, it is possible to pass a bed into and out of said room thus provid- 35 ing a large open room for use during the day as a living room and one which at night may be readily converted into a sleeping apartment. Through the provision of com- 40 panion beds, one of said beds may be used in said large room, and the other of said beds in an adjacent room, preferably a bedroom, and during the daytime said beds may be as- 45 sembled in the bedroom leaving the large room wholly free for use as a living room.

Figs. 1 to 6, inclusive, illustrate the manner in which the beds co-act to economize space in a building. Thus, the dividing wall 11, between two adjacent rooms, is provided 45 at its base with an opening 12 of a height sufficient to permit the passage of one of the companion bed units when it is in lowered position. A suitable slide or panel 13 may be used to close the opening between the two 50 rooms when the beds have been transferred to the room desired.

As is clearly shown in Figs. 1 to 6 of the drawing, the companion beds comprise two bed units 21 to 22, respectively, one unit being adapted to be lowered and the other being adapted to be raised in order that said beds may be placed one beneath the other in nested position, as is clearly shown in Fig. 6.

The details of the mechanism whereby the 60 beds are controlled forms the subject matter of a separate application Serial No. 632,551, filed April 16, 1928, but, as is shown in the drawing, each bed is provided with extension legs 23, of the plunger type and controllable 65 by means of a system of compensating mech-

anism 24 secured beneath the central portion of the frame of each of the beds. This mechanism is designed to resiliently balance the bed at an intermediate point upon the plunger legs, and it is shiftable upwardly or downwardly therefrom with but slight effort applied to any part of the bed frame. A trigger operated latch 83 is provided to secure the horizontal portion of the bed at the desired elevation. The details of the mechanism whereby the respective bed units are raised and lowered are fully set forth in my co-pending application to which reference is made for a more complete disclosure.

As will be most readily seen in Fig. 7, 70 each of the companion bed units comprises a bed frame 31 of substantially standard design, excepting that the legs at each of the ends are abbreviated. The bedstead illustrated is a metal bedstead although bedsteads of wood or of any period of design 75 may be constructed in accordance with the invention. The companion bed units may be of the same size, with extension legs 80 fitted to the inner and outer ends of the lower and upper beds respectively, as shown in Fig. 2, or they may be made in graduated sizes.

As shown in the drawing, the bow frames 32, 33, forming the head and foot portions 95 respectively of the bed, terminate a short distance below the side rails 34, 35, respectively. Upon each vertical portion of the head and foot members which constitute the end posts of the bed, telescoping leg mechanism is applied. The telescopic leg members 100 may be placed within the corner posts of the bedstead or attached to the sides therof. These telescoping or plunger legs are best illustrated in Figs. 11 and 12, and comprise 105 the plunger leg proper and a sleeve portion 36 slidably engaging the upper ends thereof, adapted to be secured by means of a specially designed clasp to the respective corner posts 110 of the bed. The clasps are shown in detail in Figs. 14, 15 and 16, and comprise an inner and outer plate 38, 39, respectively, 115 adapted to be secured to its designated corner posts by means of a headed bolt 40. The outer plate 39 is adapted to embrace two 120 sides of the corner post when the latter is of rectangular cross-section and is provided with a flat face 41 positioned diagonally of the corner of the post to which it is applied. Adjacent the side edges of the flat face, 125 grooves 42 are provided upon each side face of said plate, which grooves are adapted to be engaged by appropriately shaped terminal edges on clamping members 43 adapted to be secured thereto by means of bolts 44 extending through said clamping members and having their central portions resting in transverse recesses 45 formed in the outer supporting plates 39. The outer ends of the 130 clamping members are of concave shape and

125
130

are adapted to embrace the sleeve 36 of the telescoping or plunger leg. Thus it will be noted that manufacturers of beds of standard design may supply a bed of the type herein described by shortening the standard legs thereon and applying the plunger legs in the manner just described. Within the sleeve the main portion of the plunger leg 46 is received. As is clearly shown in Fig. 10, 12, the upper portion of the main section of the plunger leg is provided with a recess 47 within which the upper end of a cable 48 is adapted to be secured by means of a set screw 49 operating in a screw-threaded aperture 50 at right angles to said recess. A channel 51 is provided at one side of the plunger leg to accommodate the cable which is extended downwardly from its upper end and about a pulley 52 mounted in a box 53 adjacent the lower end of the sleeve. The method of supporting the pulley upon the sleeve is illustrated in Fig. 13 and comprises a metal strap 54 curved to extend about the sleeve and having apertured extension ends 55 through which a two-part fastening member 56 is adapted to extend. Said fastening member has a cylindrical central section serving as the axle of the pulley and a positioning and holding means for the pulley box. Immediately beneath the pulley box a sleeve 57 is provided for housing the trigger latch mechanism of the device. This mechanism comprises a latch bar 58 provided adjacent its forward end with a shoulder 59 against which an expansion coil spring 60 housed within said sleeve is adapted to bear. An annular plug 61 screwed into the rear end of the sleeve serves as an abutment for the other end of said spring. The rearward end of the trigger bar is provided with an eye 62 within which is fastened a trigger cord 63. The plunger leg is provided with a plurality of recesses, 64, 65, formed in the bottom of the channel provided for the operating cable. These recesses are of a size suitable to be engaged by the forward end of the latch bar which thus serves to lock the sliding portion of the plunger leg in its uppermost and lowermost position. A tapered axial socket 66 is provided in the bottom of the plunger leg to receive the extension shank of the castor 67 which may be of the standard construction. A set screw 68 is shown in Fig. 12 engaged within a recess disposed at right angles to said tapered socket 66 and may be adjusted to securely clamp the castor in operative relation to the plunger leg.

As is shown in Fig. 18 a tongue strip 69 may be inserted within the sleeve to serve as a means for centering the operating cable and guiding the plunger leg in its travel up and down in said sleeve. In Fig. 19 is illustrated a modified form of means for maintaining the operating cable in a central

position, said means comprising a pair of studs 70 having their inner ends rounded and provided with screw-threaded sections adjacent their base whereby the operating cable may be maintained in position and the plunger leg guided up and down in the sleeve.

As is shown in Fig. 7 particularly the counter-balancing means for facilitating the ready adjustment of the horizontal portion of the bed to different heights comprises a spring and cable mechanism appropriately supported beneath the usual position of the bed spring. As is shown in Fig. 7, the central portions of the side rails of the bed are connected by means of a cross-bar 71. Centrally of this bar, as is more clearly shown in Fig. 10, an upstanding stud 72 is provided which serves as a shaft upon which a pair of superposed pulley wheels 73, 74, are adapted to turn. The lower end of said stud projects downwardly and is fastened to the base of a channeled guide bar 26, hereinafter to be described. The upper pulley wheel 73 is provided with an extension sector 75 having a grooved flange within which is secure the main power applying cable 76 for said pulley. The opposite end of said cable is extended over a pulley 77 supported upon a bracket 78 secured to one of the side rails 35 and is securely fastened to one end of a coil spring 79 extending parallel to said side rail and having its other end attached to a bracket 80 secured to the opposite end of said side rail. The main portion of the pulley 73 is provided with a groove of adequate size to receive four operating cables 48 which extend to the respective plunger legs at the respective corners of the bed, as has been heretofore mentioned. The outer ends of said operating cables are secured within the recesses formed in the ends of each of said plunger legs and the inner ends of said cables are secured, at appropriately spaced points, to the pulley wheel 73. It will readily appear that any desired fastening means for the cables may be employed.

Upon each of the operating cables 48 a plurality of hangers 81 is secured, said hangers serving to sustain and guide the trigger cords 63 extending to the respective latch bars 42, as heretofore described. The inner ends of said trigger cords are secured at appropriately spaced intervals about the grooved periphery of the second pulley 74 mounted upon the stud 72 and may thus be operated simultaneously to release said latch bars from the recesses 64 or 65, in the plunger legs with which they may be engaged. The means for operating the pulley 74 comprises a lever arm 82 secured to said pulley and pivotally connected at its outer end with an operating bar or trigger 83, which extends from said counter-balancing mechanism to a convenient position upon one of

the side rails of the bed. Thus, by shifting said trigger bar the latch bars may be simultaneously withdrawn from the recesses in the plunger legs and the body portion of the bed will thus be left free for movement in a vertical direction. It is intended to have the tension upon the spring so adjusted that the body portion of the bed will be normally maintained at an intermediate position between the two limits of adjustment indicated by the respective recesses 64, 65, in the plunger legs. Thus, by merely releasing the trigger, the horizontal portion of the bed will move one-half the distance in the reverse direction and only a small degree of pressure or lifting tension will be required to move the same the balance of the desired distance. Furthermore, the pressure or lifting tension, as the case may be, according to the direction of motion in which it is desired to move the body portion of the bed, may be applied at practically any point about the bed frame, inasmuch as the counter-balancing mechanism serves to equalize the power and distribute the same to the several moving parts.

In the form of construction illustrated in Fig. 9, the supporting members for the central mechanism comprises a cross-bar 91, as well as a pair of diagonal bars 92, 93, and an inverted U-shaped channel-bar 26. The channel-bar is adapted to engage over the upstanding side of an angle bar 27, the other side of which is fastened to the floor, at a point where it is desired to store the bed unit so equipped.

The coil spring 90 in Fig. 9 is preferably housed within a guard member 95, which serves to protect anyone handling the bed from injury.

When the adjoining rooms are each used for sleeping purposes the beds will appear as they are shown in Fig. 1. When, however, it is desired to use the larger room as an open living room, through the retraction of the latch and the application of slight pressure upon the horizontal section of the bed 21, the same may be lowered to the floor level, as is shown in Fig. 2. At the same time, the bed 22 in the adjacent room is elevated by releasing the trigger latches and applying a slight amount of lifting tension to the horizontal portion of the bed until it has been raised to a height sufficient to permit the first mentioned bed to be rolled immediately beneath the last mentioned bed, when the latches will automatically snap into their sockets and maintain the upper bed in its raised position. When the beds are so assembled, the upper bed may be used, if desired, for sleeping purposes, although it will be at a slightly higher level than that at which it is intended to be positioned when ready for use.

In Fig. 5 is illustrated a modified form of the companion bed units. In said form the bed intended to be stored beneath the other is made of lesser width than its companion unit and the plunger legs of the larger unit are positioned inside of the side frame members of the larger unit.

In addition to the use of the invention in connection with a house apartment, its adaptability for the equipment of institutional dormitories, hospital wards, hotels, homes and ordinary apartments, is clearly apparent.

In order to facilitate the moving of the lowermost bed unit into proper position beneath its elevated companion unit, a guide member 26, preferably an inverted U-shaped channel-bar, is provided upon the under side of the frame of said lower unit, which guide member is adapted to engage with a co-operating guide member 27, preferably an angle bar, secured to the flooring of the room within which the beds are to be stored and terminating at a point centrally of the opening in the dividing wall between the two rooms. See Figs. 1, 2 and 6. The details of the construction of the co-acting guide elements are set forth in my companion application above referred to.

Thus it will be evident that through the construction whereby the flooring extends continuously through the opening into each of the adjacent rooms upon a single level, the lowered bed unit may be readily moved into storage position in the room reserved as a bedroom. The guide member provided on the floor of the second room makes it possible to move the bed quickly through said opening after the channeled guide bar on the bed is engaged over the upstanding edge of the angle bar on the floor. The channeled guide bar may be provided with an enlarged opening at its forward end to facilitate the engagement of the co-acting parts.

It will be noted that when the beds are in stored position that they are in substantially the same free position in a room as when they are ready for use for sleeping purposes, inasmuch as they are not enclosed in any dark air-tight recess or closet and stand out in the room with ample opportunities for ventilation and free access of light and air. If desired, the beds may be set out separately in the bedroom. The lowermost bed unit may be elevated at any time a sufficient distance to disengage the guide members and thus free said unit for movement in any direction desired.

Other modes of applying the principle of my invention may be employed instead of the one explained, change being made as regards the structure herein disclosed, provided the means stated by any of the following claims or the equivalent of such stated means be employed.

I therefore particularly point out and distinctly claim as my invention:—

1. In a building construction for apartments with companion beds, the combination with two adjacent rooms separated by a wall having an opening at and immediately adjacent the position of the baseboard, a flooring extending continuously through said opening into each of said rooms upon a single level, of companion beds comprising two entirely separable, individually complete units, means associated with one of said units for adjusting the same to a height permitting it to be passed through said opening, and means associated with the other of said units for elevating the same to receive said first mentioned unit in nested position therebeneath.

2. In a building construction for apartments with companion beds, the combination with two adjacent rooms separated by a wall having an opening at and immediately adjacent the position of the baseboard, a flooring extending continuously through said opening into each of said rooms upon a single level, of a closure for said opening, companion beds comprising two entirely separable, individually complete units, means associated with one of said units for adjusting the same to a height permitting it to be passed through said opening, and means associated with the other of said units for elevating the same to receive said first mentioned unit in nested position therebeneath.

3. In a building construction for apartments with companion beds, the combination with two adjacent rooms separated by a wall having an opening at and immediately adjacent the position of the baseboard, of a flooring extending continuously through said opening into each of said rooms upon a single level, a guide member secured to said flooring at right angles to said opening, two entirely separable, individually complete companion bed units adapted to occupy the same floor space when in nested position, and means upon one of said bed units for co-operating with said guide member to control the movement of said bed unit through said opening.

4. In a building construction for apartments with companion beds, the combination with two adjacent rooms separated by a wall having an opening at and immediately adjacent the position of the baseboard, of a flooring extending continuously through said opening into each of said rooms upon a single level, a guide member secured to said flooring at right angles to said opening and having one end terminating at a point adjacent thereto, two entirely separable, individually complete companion bed units, means for adjusting the vertical height of

the horizontal frames of said bed units whereby the same may be placed one beneath the other to occupy the same floor space, and a guide member upon one of said bed units for engaging said floor guide member when said unit is in lowered position.

5. A building construction having in combination two adjacent rooms adapted to serve respectively as a bed room and a day room, a separating wall having a large unbroken upper area and provided at and adjacent the position of the baseboard with an opening of somewhat more than normal baseboard height, a flooring extending continuously through said opening into each of said rooms upon a single level, means for closing said opening having substantially the structure and appearance of the baseboard as seen from the day room, a pair of entirely separable, individually complete companion bed units adapted to be assembled in nested relation in said bed room and being of greater and lesser size respectively, the bed unit of greater size having a normal and an elevated nesting adjustment, the unit of lesser size having a normal and a lowered nesting adjustment, said last-named unit being adapted when in lowered position to pass through said opening into either of said rooms, and the other of said units being adapted when in elevated adjustment to co-operate with said opening to receive the unit in lowered adjustment when it is moved through said opening from said day room into said bed room and to conceal said unit and also the opening in said baseboard.

6. A building construction having in combination two adjacent rooms adapted to serve respectively as a bed room and a day room, a separating wall having a large unbroken upper area and provided at and adjacent the position of the baseboard with an opening of somewhat more than normal baseboard height, a flooring extending continuously through said opening into each of said rooms upon a single level, a pair of entirely separable, individually complete companion bed units adapted to be assembled in nested relation in said bed room and being of greater and lesser size respectively the bed unit of lesser size having a normal and a lowered nesting adjustment, and being adapted when in lowered position to pass through said opening into either of said rooms, and the unit of greater size being adapted to co-operate with said opening to receive the other unit in lowered adjustment when it is moved through said opening from said day room into said bed room and to conceal said unit of lesser size and also the opening in said baseboard.

Signed by me, this 5th day of April, 1923.
HENRY B. LITTLEFIELD.
